(57) **CLAIM**

The ornamental design for a digital camera, as shown and described.

DESCRIPTION

FIG. 1 is a front, top, and right side perspective view of a first embodiment of a digital camera showing our new design;

FIG. 2 is a rear, top, and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a front, top, and right side perspective view of a second embodiment of a digital camera showing our new design;

FIG. 10 is a rear, top, and left side perspective view thereof;

FIG. 11 is a front view thereof;

FIG. 12 is a rear view thereof;

FIG. 13 is a top plan view thereof;

FIG. 14 is a bottom plan view thereof;

FIG. 15 is a right side view thereof;

FIG. 16 is a left side view thereof;

FIG. 17 is a front, top, and right side perspective view of a third embodiment of a digital camera showing our new design;

FIG. 18 is a rear, top, and left side perspective view thereof;

FIG. 19 is a front view thereof;

FIG. 20 is a rear view thereof;

(Continued)

FIG. 21 is a top plan view thereof;
 FIG. 22 is a bottom plan view thereof;
 FIG. 23 is a right side view thereof; and,
 FIG. 24 is a left side view thereof.

The features shown in broken lines in the drawings illustrate portions of the digital camera that form no part of the claimed design. The dash-dotted lines denote the boundary of the claim and form no part of the claimed design.

1 Claim, 24 Drawing Sheets
